UNITED STATES PATENT OFFICE.

LOUIS STRAUSS, OF BROOKLYN, NEW YORK.

DESIGN FOR A SWEATER.

Application filed January 14, 1922. Serial No. 198. Term of patent 3½ years.

To all whom it may concern:

Be it known that I, LOUIS STRAUSS, a citizen of the United States, and a resident of Brooklyn, in the county of Kings and State of New York, have invented a new, original, and ornamental Design for a Sweater, of which the following is a specification, reference being had to the accompanying drawings, forming part thereof.

Drawing.

The figure is a perspective view of a sweater showing the same as worn, the representation of the human form being indicated in dotted lines.

The design shows a sweater having a body of one color with a central vertically disposed panel in the front thereof, the panel being of a corresponding material but different color.

I claim:

The ornamental design for a sweater as shown and described.

LOUIS STRAUSS.
